F. A. GRITT

ROTARY ILLUMINATED MOTION SIGN

Filed Nov. 11, 1927

Patented May 22, 1928.

1,671,072

UNITED STATES PATENT OFFICE.

FRANK A. GRITT, OF INDIANAPOLIS, INDIANA, ASSIGNOR TO GRITT, RAGSDALE AND CO., OF INDIANAPOLIS, INDIANA, A CORPORATION OF INDIANA.

ROTARY ILLUMINATED MOTION SIGN.

Application filed November 11, 1927. Serial No. 232,503.

My invention is concerned with illuminated display devices of the type in which a picture is projected onto a screen in such a manner that the parts of the picture appear to move relatively to other parts. Such devices are well known and usually embody a primary translucent screen on which there appears a part or all of the picture to be displayed, a light-source located behind this screen, a secondary screen located between the light-source and the primary screen and having portions of varying light-transmitting capacity, which portions may form parts of the complete picture if all such picture does not appear on the primary screen, and means located between the light source and the secondary screen for producing alternate bands of light and shadow which travel over such secondary screen and produce on the primary screen complete picture parts of which appear to move relatively to other parts or to the screen.

It is the object of my invention to produce a display device which will display more than one picture, which may be simply and economically constructed, and which will occupy substantially no more space than is required for a display device embodying but one picture.

I accomplish the above objects by making the primary and secondary screens referred to above in the form of concentric cylinders the surfaces of which are divided longitudinally into separate picture screens, and within this cylinder I locate the light-source and the means for producing the moving bands of light and shadow. Desirably, I provide means for rotating the two cylindrical screens slowly in order that all pictures may be presented successively.

The accompanying drawing illustrates my invention: Fig. 1 is a longitudinal section through my complete display device; Fig. 2 is a transverse section on the line 2-2 of Fig. 1; and Figs. 3 and 4 are elevations of corresponding outer and inner screen-sections.

In the preferred form of my invention, those parts of each picture which are to appear stationary on the outer or primary screen are painted or otherwise reproduced thereon, while the picture parts which are to appear to move relatively to the screen and to the stationary parts are carried by the corresponding inner screen. This means of

simulating motion in pictures is described in greater detail and claimed in my co-pending application Serial No. 141,543, filed October 14, 1926.

I prefer to construct my new display device in such a manner that it may be hung or suspended as by means of a chain 10 although any other convenient mounting means may be employed. When the chain 10 is used, I attach to its lower end a hollow member 11 on the lower end of which is mounted a frame 12 which serves as a support for the light-source and for the means by which the screens are located. Near the bottom of this frame I provide a downwardly extending projection 13 to the lower end of which is secured a socket 14 for a light bulb 15.

The means by which rotation of the screen is effected may be of any kind desired; but when alternating current is available, I prefer to employ the simple form of motor illustrated in the drawing. This motor includes an electro-magnet 17 having an asymmetrical pole piece 18 located in proximity to a rotatable disk 19 of non-magnetic material. The disk 19 is conveniently carried by a shaft 20 which is rotatably supported in suitable bearings in the frame 12. The eddy currents set up in the disk 19 by the effect of the alternating current in the electro-magnet 17 produce a slow rotation of the disk.

Rotatably mounted on the member 11 and frame 12, I provide a gear 22 arranged to mesh with a pinion 23 mounted on the shaft 20. From this gear 22, I support a frame on which the primary and secondary screens or transparencies are carried. This frame may be constructed in any desired manner, but I prefer to form it of a plurality of rings 25 held in position by means of longitudinally extending bars 26. The bars 26 are desirably provided in their side faces with longitudinal extending grooves adapted to receive the edges of the outer transparencies 27, as is clear from Fig. 2. In addition, there may also be inserted in such grooves sheets of clear transparent material 28 which serve as supports for the outer transparencies 27.

Within the rings 25 and secured to them and to the parts 26 are inner rings 30 between which there extend inner bars 31. These inner bars 31 like the outer bars 26, are provided with longitudinally extending grooves

in their side faces in order that they may support the inner screens or transparencies 33.

The hollow frame formed by the various rings and bars may be supported from the gear 22 by means of a cross-member 34 which extends diametrically across the upper ring 25 and rests on the gear 22 in order that it and the entire frame may rotate with such gear.

As set forth in my prior application above referred to, I provide a means for producing alternate bands of light and shadow which move across the inner and outer screens 33 and 27. This means may take various forms, but I prefer to employ the rotor 35 illustrated in the drawing. This rotor, as set forth in my prior application, is conveniently formed of some sheet metal generally in the form of an inverted cup surrounding the lamp bulb and provided with a circular series of slots 36 which extend from near the bottom of the cup upward along the sides thereof and inward at the top thereof toward the center. These slots may be of any desired shape, but are desirably oblique curves as shown in the drawing.

The rotor 35, while capable of being rotated by the upward current of air heated by the light bulb 15 is desirably driven from the shaft 20. To this end, I provide the rotor 35 with an upwardly extending annular projection 37 adapted to be received within a split sleeve 38 carried by a gear 39 which is arranged to be driven from the shaft 20, as by means of the pinion 40 and idler gear 41.

When I construct my device to employ the principle of the invention set forth in my aforesaid prior application Serial No. 141,543, I form the two screens 27 and 33 of transparent or translucent material, such as paper, parchment, or celluloid. Both transparencies carry portions of the desired picture, those portions which are to appear stationary relatively to the outer screen being carried by that screen, while those picture-portions which are to appear to move are carried by the inner screen. Thus, in the case of the screens illustrated in Figs. 3 and 4, the outer screen 27 bears a representation of a coffee can 40 and a cup and saucer 41; while the inner transparency 33 bears a representation of steam 42 arising from the cup 41 to form a suitable advertising legend. Desirably the rear or inner transparency 33 is blank behind the stationary-appearing picture-portions on the front or outer transparency 27, and this outer transparency is blank in front of the moving appearing portions on the inner transparency, as is clear from a comparison of Figs. 3 and 4.

As the rotor 35 rotates, alternate bands of light and shadow are caused to pass over the transparencies, and this results in simu-

lating on each outer transparency an appearance of movement of those picture-portions carried by the corresponding inner transparency. As the screen-bearing frame is rotated with the gear 22, the various pictures are successively presented to an observer.

The cylindrical arrangement of the inner and outer transparencies gives to the construction described herein an advantage not possessed by the device of my prior application; for as a result of curving the two transparencies the side edges thereof are substantially the same distance from the light-source and rotor as is the center of the picture. This results in sharper definition and a more regular appearance of motion.

While I prefer to produce the appearance of motion of certain picture-portions by utilization of the principle embodied in the invention of my aforesaid application Serial No. 141,543, this is not essential; as the appearance of motion can also be obtained, as is well known, by placing the entire picture on the outer screen and by having the intermediate screen consist of alternate transparent and semi-transparent or opaque portions, or other light-modifying markings.

I claim as my invention:—

1. An illuminated display device, comprising a rotatable hollow frame, means for rotating said frame, a plurality of primary transparencies, said frame having a circumferential series of openings in which said primary transparencies are mounted, a source of light within said frame, a plurality of secondary transparencies each mounted in said frame between its associated primary transparency and said light source, said primary transparencies having picture parts which are to appear stationary and said secondary transparencies having picture parts which are to appear as moving, and a movable screen having thereon light-transmitting portions between said light source and said secondary transparencies.

2. An illuminated display device, comprising a rotatable hollow frame, means for rotating said frame, a plurality of primary transparencies, said frame having a circumferential series of openings in which said primary transparencies are mounted, a source of light within said frame, a plurality of secondary transparencies each mounted in said frame between its associated primary transparency and said light source, said primary transparencies having picture parts which are to appear stationary and said secondary transparencies having picture parts which are to appear as moving, and a rotatable screen surrounding said light-source and having light-transmitting portions.

3. An illuminated display device, comprising a rotatable hollow frame, a plurality

of primary transparencies, said frame having a circumferential series of openings in which said primary transparencies are mounted, a source of light within said frame, 5 a plurality of secondary transparencies each mounted in said frame between its associated primary transparency and said light source, said primary transparencies having picture parts which are to appear 10 stationary and said secondary transparencies having picture parts which are to appear as moving, a screen surrounding said light-source and having light-transmitting portions, and common means for rotating 15 said frame and said screen at different speeds.

4. An illuminated display device, comprising a light-source, inner and outer transparencies arranged around said light source and bearing respectively picture parts which are to appear stationary and picture parts which are to appear as moving, a rotatable screen surrounding said light-source and having light-transmitting portions, and means for rotating said transparencies in unison and for rotating said screen. 20 25

In witness whereof, I have hereunto set my hand at Indianapolis, Indiana, this 1st day of November, A. D. one thousand nine hundred and twenty seven.

FRANK A. GRITT.
